(57) **CLAIM**

The ornamental design for an oxygenerator, as shown and described.

DESCRIPTION

FIG. 1 is a front, right and top perspective view of an oxygenerator showing our new design;
FIG. 2 is a rear, right and top perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof; and,
FIG. 9 is an exploded view showing a separable configuration thereof.
The broken lines depict portions of the oxygenerator that form no part of the claimed design.
